Assistant Examiner — Clare Ann Gannon

(57) **CLAIM**

The ornamental design for a maternity belt, as shown and described.

DESCRIPTION

FIG. 1 is a front view showing my new design;
 FIG. 2 is a rear view thereof;
 FIG. 3 is a front view thereof, shown in an unfolded configuration; and,
 FIG. 4 is a rear view thereof, shown in an unfolded configuration.

The broken lines in the figures illustrate portions of the maternity belt that form no part of the claimed design.

1 Claim, 4 Drawing Sheets
